UNITED STATES PATENT OFFICE.

THOMAS PUGH MARTIN, JR., OF OKLAHOMA, OKLAHOMA.

LOOSE-LEAF PASS-BOOK.

1,254,052.

Specification of Letters Patent. Patented Jan. 22, 1918.

Application filed December 29, 1916. Serial No. 139,497.

To all whom it may concern:

Be it known that I, THOMAS P. MARTIN, Jr., a citizen of the United States, and a resident of Oklahoma city, in the county of 5 Oklahoma and State of Oklahoma, have made an Improvement in Loose-Leaf Pass-Books, of which the following is a specification.

My invention is a loose-leaf pass-book particularly adapted for the use of bank depositors.

The details of construction are as herein-after described and shown in the accompanying drawing, in which,

15 Figure 1 is a plan view of the inner side of the cover of the pass-book.

Fig. 2 is a perspective view of my entire loose-leaf folded lengthwise and transversely as required for attachment to the cover of 20 the pass-book.

Fig. 3 is a plan view of a portion of a sheet with credit entries thereon.

Fig. 4 is a plan view of the pass-book with loose leaves secured thereto by detachable 25 fastenings.

Fig. 5 is an enlarged sectional view of a portion of the pass-book on the line 5—5 of Fig. 4.

In Fig. 1 the pass-book cover 1 is shown 30 open and provided with an elastic band 2, extending from end to end, for securing loose leaves removably thereto; also, with an opening 3 in one side through which the name of the owner of the pass-book will appear when loose leaves are secured to the 35 cover.

The loose leaves 4 are ruled as shown in Figs. 2 and 3, and folded once transversely and twice lengthwise. Printed headings appear on each side of the sheet. Thus at the 40 top of half of the column the title "Credits" appears, and on the other half the title "Checks" is shown, in Fig. 3.

In Fig. 1 the cover is shown provided with 45 an opening 1* at the top of one side, and loose leaves 4 have a corresponding opening 4* to provide for the use of the well known dress or glove fastening shown applied, in detail, in Fig. 4, a knob-like head being 50 shown as entering a spring socket whereby it is held detachably, as will be readily understood.

As illustrated in Fig. 4 a series of such fastenings is applied on a horizontal line at 55 the upper end of one side of the cover, so that the loose leaves 4 are held detachably

with their side edges parallel to the edges of the cover.

A rubber band 2 is attached at its ends to the ends of the hinged cover as an additional 60 means for holding a folded leaf or leaves in due position. The band may be attached at one side of the cover hinge so as not to interfere with the folding of the leaf or leaves.

Under my system the leaves are removable 65 from the book cover at any time and may be placed on an adding machine and balanced, and then the sheet or sheets replaced, so as to start a new page of entries; or, if the bank book-keeper does not wish to wait for the 70 customer's pass-book to come in at the end of the month, he may take a new sheet from the stationary cabinet, put down the deposits from the original slips on file at the bank, also put down the checks, and balance the 75 account and enter the balance at the top of the new page of the loose leaf. When a customer comes in, the teller may slip out the old sheet and put in a new one, the latter showing the entire dealings for the month 80 previous, and thus start off with a new sheet.

While the system is especially adapted to adding machines, it may be readily used with pen and ink. The teller puts down deposits with pen and ink and later when the 85 bookkeeper gets the particular sheet on which the deposits are entered, he adds up the deposits on the credit side, then usually balances the other on the adding machine. Rulings are made to conform to adding machine spaces or not, as may be desired, but naturally it is preferable to rule for adding machine work.

As has been before stated, the first half of a page is for credits, and the other half for 95 checks. The "credit" side has room for more deposits per working month than will actually be needed and being double spaced, can take 68 deposits if necessary. The "check" side will hold about 150 checks and 100 if more space is desired the balance of the entire side of the sheet may be used and when returning the sheet, placed in the pass-book cover, the other side can be used for the next month. Thus the scheme is practically 105 extensible to any size of account.

The ruling is a distinctive feature, for by folding back after using first pages, an account starts off at top of credit side of next or succeeding page with the correct balance. 110 In each case owing to the special ruling and arrangement, the name of the depositor

comes in proper place behind the opening in the cover of the pass-book, thus giving the bank the privilege of using covers for an indefinite length of time by reason of the fact 5 that no names are written on the covers, but solely on the sheet or loose leaves. The sheets may be used as bank statements, and they may be cut in half or separated at will making smaller or large leaves, as may be 10 desired. I thus produce a combination loose-leaf pass-book and a statement which permits the sheets or leaves to be removed or retained in the cover, whichever may be desired. Thus the book may be used as a pass-book, or as a statement, and the same sheets 15 can be used for personal statements, where pass books are balanced by totals or otherwise. The cover is made of any suitable material, having due degree of rigidity.

20 My main idea is the provision of a loose-leaf pass-book and a statement sheet which will do away with much of the expense incident to banks furnishing large bodied pass-books to customers who run an account only 25 a few days. My greatest object is to save time to bank bookkeepers who under my system do not have to wait for pass-books to come in but can get loose sheets from their stationery cabinet, make out the customer's 30 account, balance it up and have these sheets with the checks ready when the old pass-books come in, or, if desired, an entirely new cover may be applied to the newly balanced sheet and exchanged with the customer when he comes in. By this method the 35 accumulation of a large number of pass-books at the bank to be balanced is avoided.

I claim:

1. A bank pass-book comprising a foldable cover and detachable leaves, each leaf having two major portions ruled respectively to receive deposit and check accounts, each leaf being folded to be received into the said cover to present the deposit account open, the cover having means detachably securing the leaves, as shown and described. 40
2. The improved loose leaf bank pass-book comprising a foldable cover, a loose leaf having portions respectively printed for deposit and check accounts, and adapted to an adding machine, said leaf being folded and received in the cover to present the deposit account open, and means for detachably securing said leaf to the cover, substantially as described. 50
3. The improved loose leaf bank pass-book comprising a foldable cover, a loose leaf having portions respectively printed for deposit and check accounts, and adapted to an adding machine, for the direct entry of the 60 amounts of separate checks, the cover being arranged to receive the leaf and present the same with the deposit account open, as described. 55
4. The improved loose leaf bank pass-book comprising a foldable cover, a loose leaf having a plurality of portions respectively printed for deposit and check accounts, and adapted to an adding machine, said leaf being folded and received in the 70 cover to present the deposit account open, and means for detachably securing said leaf to the cover, substantially as described. 65

THOMAS PUGH MARTIN, JR.
